(57) **CLAIM**

The ornamental design for a speaker for personal computer, as shown and described.

DESCRIPTION

FIG. 1 is a perspective view showing a frontal side of the speaker for a personal computer;

FIG. 2 is a front elevational view of the speaker for a personal computer;

FIG. 3 is a rear elevational view of the speaker for a personal computer;

FIG. 4 is a left side elevational view of the speaker for a personal computer;

FIG. 5 is a right side elevational view of the speaker for a personal computer;

FIG. 6 is a top plan view of the speaker for a personal computer;

FIG. 7 is a bottom plan view of the speaker for a personal computer;

FIG. 8 is a front elevational view of FIG. 2, with the upper part of the speaker rotated to a 90° position;

FIG. 9 is a front elevational view of FIG. 2, with the upper part of the speaker rotated to a 270° position;

FIG. 10 is a front elevational view of FIG. 2, with the upper part of the speaker rotated to a 180° position; and,

FIG. 11 is a right side elevational view of FIG. 5, with the upper part of the speaker in an alternate position.
